STORE BUILDING FAÇADE

Joseph Binder, Oceanside, and Carrl Palestini, Lido Beach, N.Y., assignors to The Bohack Corporation, Brooklyn, N.Y.

Filed Aug. 16, 1972, Ser. No. 281,141
(Filed under Rule 47(a) and 35 U.S.C. 116)

Term of patent 14 years

Int. Cl. D25—03

U.S. Cl. D13—1 B

FIG. 2

FIG. 4

FIG. 3

FIG. 4

FIG. 1 is a perspective view of a store building facade of our invention, illustrating the front and one side thereof;

FIG. 2 is a top plan view of the store building facade of our invention;

FIG. 3 is a front elevational view of the store building facade of our invention;

FIG. 4 is a side elevational view of the store building facade of our invention, the side of said store building facade illustrated in this elevational view being disposed at the right-hand end of the store building facade illustrated in FIG. 3;

FIG. 5 is another side elevational view of the store building facade of our invention, the side of said store building facade illustrated in this elevational view being disposed at the left-hand end of the store building facade illustrated in FIG. 3.

What is claimed is:

The ornamental design for a store building facade, as shown.
